INVENTOR.

Lorenzo D. Varnell

UNITED STATES PATENT OFFICE.

LORENZO D. NEWELL, OF PROVIDENCE, RHODE ISLAND.

SELF-LEVELING BERTH.

SPECIFICATION forming part of Letters Patent No. 276,867, dated May 1, 1883.

Application filed June 14, 1882. (No model.)

To all whom it may concern:

Be it known that I, LORENZO D. NEWELL, a citizen of the United States, residing at Providence, in the county of Providence and State of Rhode Island, have invented certain new and useful Improvements in Self-Leveling Berths for Vessels; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to a self-leveling berth for vessels, which is designed to maintain a horizontal position while the vessel may be rolling and pitching.

My invention consists of a cylindrical frame, 20 open on top, in which the berth is suspended.

My invention further consists of an adjustable counterpoise or weight suspended from the transverse axis of the berth, said axis being located above the center of gravity of the berth, 25 and forward of said axis.

My invention also consists of a suitable screen or guard secured outside of the cylindrical frame, whereby the motion of the berth is protected from the sight of a person occupying 30 the lower berth or other occupants of the state-room.

My invention also includes peculiar locking devices for connecting the frame and berth together and also to the state-room.

35 In the accompanying drawings, Figure 1 represents a side elevation, partly in section, of my berth, showing the different parts in position constituting my invention. Fig. 2 is a vertical transverse section on line A B of Fig.

40 1, showing the adjustable weight and also the device for locking the cylindrical frame to the state-room. Fig. 3 is a partial plan section on line x x, showing the device for steadyng the berth. Fig. 4 is a partial plan section on line 45 w w, showing the device for locking the berth and frame together.

A in the drawings represents the cylindrical frame, open on the top side, in which the berth is suspended, made of wood or suitable 50 material, said frame being suspended at each end thereof from trunnions or journals a, se-

cured to the state-room walls, said trunnions having collars a' secured thereto, which, taken in connection with the bearings a'', secured at each end of said frame, and in the axial center thereof, serve to connect the frame and state-room walls together, thereby strengthening and stiffening the same and also preventing undue longitudinal motion of the frame.

H represents a circular bead or molding, secured at opposite sides of the state-room, into which the ends of the frame extend, thereby forming an ornamental finish, and is also utilized for securing the guard or screen I thereto, the latter serving both as a sight-protector and strengthening-brace to the berth and state-room.

C represents a cleat or brace, being an extension of the guard I, secured at each end of the state-room, extending across and in front of the cylindrical frame, the top edge of which serves as a shelf or seat to persons entering or leaving the berth, and contains the locking-bolt for connecting said frame and state-room together. Said brace can also be used upon its top side for supporting a rod across which a curtain may be made to extend.

B represents the berth, which is suspended inside the cylindrical frame A and on opposite sides thereof by trunnions or journals b, said journals having flanges b', which serve to secure it to the berth. b' are collars upon the ends of said journals, which serve to prevent lateral motion, and also to loosely secure the frame and berth together. b'' represents the bearings for said journals, which are secured to the inside of said frame A. The journals b are located above the center line of the frame A, and at a short distance nearer the head end of the berth than the foot, as shown. At b' the four corners of the under side of the berth are cut away diagonally, as shown, thereby allowing greater vertical motion to the berth.

S are buffers or stops, made of rubber or other elastic material, confined in the sockets, as shown, said buffers serving to prevent sudden or violent shocks incident to the motion of the vessel.

D represents the adjustable counter-weight, which extends across the under side of the berth, and is suspended from the journals b by

arms *d*, the upper end of said arms terminating in handles *d'*. To said handles are pivoted the secondary levers *g*, which engage with the teeth of the notched plate *h*, the latter being let into and secured to the berth *B*.

i are handles or levers secured to pins *i'*, said handles *i* having springs *d*² connected therewith, the several parts *h g i i' d' d*² constituting my adjusting device for the said weight *D*, the latter being capable of adjustment either to right or left, and to the extreme position *o o*, as shown by heavy dotted lines, whereby its center of gravity is made to extend considerably past its center of suspension.

*C' C*² represent grooved and tongued metallic strips, having a partly-circular form, secured respectively to frame *A* and berth *B*, to each side thereof at the foot end, said strips serving to reduce the strain upon the journals *b*, as well as to reduce the lateral movement of the berth.

k represents a metal plate or strip, which is let into and secured to the inside of the cylindrical frame *A* at the head end thereof, (see Figs. 1 to 4,) said strip having a notch at *l*, the outer edge thereof being well rounded, Fig. 1.

n is a lever or handle, which may be detachable, secured to the upper end of the vertical shaft or rod *m*, and having secured at its lower end the locking-bolt *l*, said shaft being supported in bearings secured to the inside of the berth *B*, and represented in the drawings as locked to the frame *A*, the object of this locking device being to connect the berth and frame together.

z represents a strip of metal similar to said strip *k*, secured to the outside of said cylindrical frame *A*, on the front side thereof and in the same vertical plane with the journals *b*,

40 &c., as shown in Fig. 2.

w is the locking-bolt, secured to the lower end of the shaft *Y*, which in turn is supported in and by the cleat *C*.

x is the handle or lever, attached to the upper end of said shaft for operating the locking bolt, the object of this locking device being to connect the frame and state-room together.

The operation of my invention is as follows: 50 The arrangement of the journals or trunnions *a a b b* of the cylindrical frame and berth admit of the latter remaining in a horizontal position (within certain limits) while the vessel may be rolling and pitching; and, further, 55 when desirable to have the motion of the berth coincident with the vessel's motion, the locking-bolts *l* and *w* are swung into position, as shown in Figs. 2 to 4. The handles *d'* serve to assist a person when entering or leaving 60 the berth; but in case of adjusting the counter-weight *D*, the fingers of the operator are made to embrace both the handles *d'* and levers *i*, when, by closing the hand, the catch *g* is raised from the teeth of the plate *h*, which then allows 65 the weight to be swung to any desired position, after which, by relaxing the fingers,

the catch *g* will engage with its corresponding notch by the aid of the springs *d*².

In the drawings, Fig. 1, my improved berth is represented as a lower one, and is located 70 near the floor, so as to allow a similar swinging berth above it.

The addition of the parts *C* I render the motion of the berth and frame invisible to the occupant of the lower berth or to other persons. 75

With my system of suspending berths I am enabled to locate the back side of the berth against the side of the state-room, thereby reducing the space required for swinging berths 80 to a minimum.

Having thus described my invention, what I claim as new, and desire to secure by Letters Patent, is—

1. In a self-leveling berth for vessels, the 85 combination of the longitudinal semi-cylindrical frame *A*, provided with trunnions *a* at the ends thereof, with the berth *B* and weight *D*, the former suspended within the frame *A* on trunnions *b*, said trunnions having loosely 90 mounted thereon the adjustable counter-weight *D*, substantially as shown and described.

2. In a self-leveling berth for vessels, the cylindrical frame *A*, suspended on journals *a*, provided with buffers *S* and strips *C'*, in combination with the cleat or brace *C*, circular molding *H*, and screen or guard *I*, substantially as shown and set forth. 95

3. In a self-leveling berth for vessels, the berth *B*, suspended on journals *b*, secured thereto, said berth having its lower corners, *b*⁵, cut off diagonally, and also provided with strips *C*², in combination with the cylindrical frame *A*, adapted to receive the journals *b*, substantially as shown and set forth. 100

4. In a self-leveling berth for vessels, the counter-weight *D*, having arms *d* and adjusting device *g i i' d' d*², in combination with the swinging berth *B*, provided with the notched plates *h*, substantially as shown and set forth. 110

5. In a self-leveling berth for vessels, the suspended semi-cylindrical frame *A*, having a notched strip or plate, *z*, secured to the exterior of said frame, in combination with the cleat *C*, the latter adapted to receive suitable 115 locking means, substantially as shown and described.

6. In a self-leveling berth for vessels, the swinging berth *B*, provided with suitable locking means, in combination with the semi-cylindrical frame *A*, the latter having a notched strip or plate, *k*, secured to the inside thereof, substantially as shown and described. 120

7. In a self-leveling berth for vessels, the suspended frame *A*, cleat *C*, molding *H*, and 125 screen *I*, the latter extending across and secured at each end to the state-room, in combination with the berth *B* and adjustable weight *D*, substantially as shown and set forth.

8. In a self-leveling berth for vessels, the 130 combination herein described, consisting of the semi-cylindrical frame *A* and stationary

guard or cleat C, the latter provided with the locking-bolt *w*, which serves to fasten said frame and cleat together, in connection with the berth B, provided with the locking-bolt *l*, which latter serves to fasten the frame and berth together, the whole constructed and arranged substantially as shown and set forth.

In testimony whereof I have affixed my signature in presence of two witnesses.

LORENZO D. NEWELL.
